J. DUNLOP,
TYPE WRITING MACHINE,
APPLICATION FILED AUG. 12, 1918.

1,293,057.

Patented Feb. 4, 1919.

4 Inventor
Judeon Dunlop
By his attorney J. H. Barker

UNITED STATES PATENT OFFICE.

JUDSON DUNLOP, OF FLORAL PARK, NEW YORK, ASSIGNOR OF ONE-HALF TO WALTER S. BARNES, OF NEW YORK, N. Y.

TYPE-WRITING MACHINE.

1,293,057.

Specification of Letters Patent. Patented Feb. 4, 1919.

Application filed August 12, 1918. Serial No. 249,412.

To all whom it may concern:

Be it known that I, JUDSON DUNLOP, a citizen of the United States, and resident of Floral Park, in the county of Nassau and

5 State of New York, have invented certain new and useful Improvements in Type-Writing Machines, of which the following is a specification.

This invention relates to typewriting machines, and my improvement is directed to means for inclosing the keyboard when the machine is not in use, and means for locking the spacer and shift keys in depressed positions, in order that no unwarranted use may 10 be made of the keyboard, for operation of the type-bars, and also to prevent longitudinal displacement or movement of the paper carriage.

Therefore my invention consists of a 20 hinged device, independent of the machine, adapted to fit over and embrace the keyboard of a typewriting machine, and to be locked thereto, to prevent its unauthorized removal.

25 Thus the finger keys are rendered inaccessible, and cannot be operated.

The device has integral members, which, when the device is closed about the keyboard, engage with portions of the machine 30 frame, and with the rear row of keys, to thus enable said device to be placed in fitting relation about said key-board, so that said device may not be shifted from the keyboard in any direction. Then, by locking

35 together the hinged members of the device, it is secured in that fitted relation about the key-board. Also, the upper, hinged member of the device is provided with depending blocks, so positioned, respectively, to de-

40 pressingly engage with the shift and back space keys, that movement of said keys is prevented and they are held depressed, whereby the carriage may become locked against longitudinal movement.

45 Other features and advantages will hereinafter appear.

In the drawing:—

Figure 1 is a plan view of a portion of a typewriting machine, with my improved 50 key-board cover applied thereto.

Fig. 2 is a side elevation thereof, and

Fig. 3 is a detail plan view of the hook engaging means.

The device is shown in the drawing as applied to an Underwood machine, merely by

way of example, it being adapted, with slight modifications in design, to apply to the key-board of other makes of typewriting machines.

In the present example, let 1 indicate the 60 machine frame, composed of horizontal side bars 2 at the base and inclined side bars 3, said bars 2 and 3 merging forwardly, and having front frame bar 4. The finger keys for the type bars are shown at 5, spacer key 65 at 6, shift key at 7, and back space key at 8. The carriage is indicated at 9, having platen 10.

My improved key-board cover consists of the members 11 and 12, which are hinged 70 together at 13, so that they may be opened out to fit over embracingly and be removed from the key-board; and be closed together about said key-board, to encompass it.

The lower member 11 of the device is a 75 frame having the base 14, front wall 15, and side walls 16, the latter increasing in height rearwardly, following approximately the rearwardly upward angle of the bank of keys.

The top member 12, which is hinged at one side, by hinge 13 to the top of a side wall 16 of member 11, has at its opposite side a depending flange 17, to take over an adjacent wall 16 of member 11, in closing thereon, 85 and also has a depending, rearward flange 18, to engage behind the rear row of finger keys of the key-board, to thus prevent removal forwardly of the device when fitted in engaged position.

The upper member 12 has a block 19 depending from its under surface, so located thereon as to lie directly over the spaced key when the device is adjusted in position, said block 19 serving to depress the spaced key 95 to the limit of its downward movement. Thus the spacer key is held against movement. Further, the member 12 is similarly provided on its under surface with blocks 20, so positioned as to lie, respectively, over 100 the shift and back space keys, to depress and lock them, and thereby to prevent movement of the carriage both vertically and longitudinally.

Obviously, with machines having different 105 arrangements of tabular and other finger keys included in the key-board, various combinations of keys may be depressed to effect the locking means aforesaid; therefore the arrangement of blocks 20 herein shown is 110

purely arbitrary and may be modified to suit the requirements.

5 The members 11 and 12 may be provided with catch devices as at 21 to hold them together when closed, and locking means may also be provided. Thus the member 11 may have a staple 22, and the member 12 a hasp 23 to fit over said staple, which latter may then receive a padlock, as 24, to secure the closure.

10 As means for snugly fitting the device to the machine, the walls 16 of the lower member 11 may be provided, on their inner surfaces, with hooks 25, so arranged as to engage with and bind upon the side bars 3 of the key-board frame, while the base 14 of said member 11 bears against the under surface of the horizontal side bars 2 of said frame. The relative spacing between the base 14 and hooks 25 is such that these members fit snugly against the side bars 2 and 3 when the member 11 is thus slidingly adjusted in position upon the machine, prior to closing down the member 12 thereon.

15 25 Variations may be resorted to within the spirit and scope of my invention, and parts thereof used without others.

I claim:—

30 1. A freely removable device for inclosing the key boards of typewriting machines, comprising upper and lower members, hinged together at one side and adapted to be embracingly fitted about a key board, to inclose the finger keys thereof, and means 35 for locking said members together at the side thereof opposite their hinged side.

2. In a device for inclosing the key-boards of typewriting machines, in combination, a

lower member to lie beneath a key-board, means upon said lower member to engage 40 with the machine frame, an upper member hinged at one side to said lower member and adapted to close upon the key-board and said lower member, means upon said upper member to engage in its closed position with 45 a row of keys, to prevent forward withdrawal, and locking means for said lower and upper members, when closed.

3. In a device for inclosing the key-boards of typewriting machines, in combination, a 50 lower member to lie beneath a key-board, an upper member hinged at one side to said lower member and adapted to close upon the key-board and said lower member, means upon said upper member to engage in its 55 closed position with a row of keys, to prevent forward withdrawal, and locking means for said lower and upper members, when closed.

4. In a device for inclosing the key-boards of typewriting machines, in combination, a 60 lower member to lie beneath a key-board, an upper member to lie over the key-board, covering the finger-keys, means upon the under surface of said upper member to de-pressingly engage some of said finger keys and thus prevent actuation of the carriage, and means for securing said members together embracingly about said key-board.

65 Signed at borough of Manhattan in the city, county and State of New York this 9th day of August, A. D. 1918.

JUDSON DUNLOP.
